H. PEPIN

LEATHER CUTTER

Filed Dec. 23, 1926

Fig. 2.

Inventor
Harvey Pepin,

By Clarence A. O'Brien
Attorney

UNITED STATES PATENT OFFICE.

HARVEY PEPIN, OF WILLIMANSETT, MASSACHUSETTS.

LEATHER CUTTER.

Application filed December 23, 1926. Serial No. 156,638.

This invention relates to new and useful improvements in leather cutters, and has for its primary object to provide a highly novel, simple, and efficient device whereby leather 5 may be properly cut without requiring the use of a complicated power driven machine.

The invention further aims to provide a leather cutter wherein the same may be regulated for cutting leather of various 10 thicknesses.

With the foregoing and other objects in view as the nature of the invention will be better understood, the same comprises the novel form, combination and arrangement of 15 parts hereinafter more fully described, shown in the accompanying drawing and claimed.

In the drawing wherein like reference characters indicate corresponding parts throughout the several views:

20 Figure 1 is a longitudinal section of a leather cutter constructed in accordance with the present invention.

Figure 2 is a detail vertical section taken through the cutting end thereof substantially 25 upon the line 2—2 of Figure 1, and looking toward the direction of the arrows.

Now having particular reference to the drawing, my novel leather cutter consists of a vertical standard 5, having a suitable base 30 6 at its lower end to facilitate the anchoring of the cutter to a work bench or other suitable support. At the upper end of this standard 5 there is formed a pair of vertically spaced horizontally extending and 35 parallel hollow shaft guides 7 and 8 that are open at their opposite ends as clearly indicated in Figure 1.

Mounted within the ends of the lower, 40 guide 8 are bearings 9—9 while arranged longitudinally within this guide is a shaft 10, the ends thereof being of increased diameter for fitting relation within said bearings as disclosed. Upon the inner end of this shaft 10 is a large gear 11, while upon the 45 opposite projecting end of the shaft is detachably disposed a milled leather feed roller 12 formed circumferentially with a V-groove 13 for a purpose to be hereinafter more fully described. To facilitate the turning of this 50 shaft 10 there is provided a hand crank 14 attached to the extreme inner end of the shaft upon which is mounted the gear 11.

The bore within the upper shaft guide 7 is considerably greater than the bore in the 55 lower guide, while within the bottom of this guide adjacent the opposite ends there-

of are sockets 15 and 16 within which are 60 slidable the lower ends of bearing blocks 15' and 16' that are formed with longitudinal and registering shaft receiving bores. Within the guide 7 is a shaft 17, the ends 65 thereof being of reduced diameter and being mounted within the bores of the bearing blocks 15' and 16' respectively. Pivoted within the bore of said guide 7 beneath the shaft 17 is an elongated lever 18 the forward 70 end of which is arranged within a longitudinal slot 19 in the bottom of the bearing block 15'. Arranged between this lever 18 and the bottom of the bore of said shaft 75 guide 7 is an expandible coil spring 20, for the purpose of normally swinging the outer end of the lever 18 upwardly for consequently forcing said bearing block 15' in an upward direction. Arranged within the 80 socket 16 for the bearing block 16' and beneath said bearing block is an expandible coil spring 21 also for the purpose of normally maintaining said bearing block in its upward limit of movement. Obviously in- 85 somuch as the ends of the shaft 17 are arranged within these bearing blocks, said shaft will also be forced upwardly by reason of the means just described.

Upon the inner projecting end of the shaft 85 17 is a gear 22, that has mesh with the previously mentioned gear 11. At this point it is necessary to state that the teeth of these gears are of such a length as to permit the upward movement of the shaft 17 together 90 with the gear 22 to the position disclosed in Figure 1 without the teeth becoming out of mesh.

Threaded within openings in the upper 95 shaft guide 7 directly above the bearing blocks 15' and 16' are wing headed set screws 23—23, which when turned inwardly will force the bearing blocks in a downward direction against the action of the springs 20 and 21 for a purpose shortly to be described.

The forward reduced end of the shaft 17 extends beyond the shaft guide 7 and is equipped at said projecting end with a removable circular cutter blade 24 in vertical alignment with the circumferential channel 13 in the feed roller 12. Obviously, by adjusting the position of the shaft 17 within the guide 7 leather strips of various thicknesses may be properly cut or may be slit as desired.

There may be, and preferably is mounted above the cutter 24 a hood 25 detachably

connected to the outer end of the shaft guide 7, this hood being obviously for the purpose of protecting the operator from the cutting blade 24.

5 In view of the foregoing description when considered in conjunction with the accompanying drawing, it will at once be apparent that I have provided a highly novel, simple, and efficient leather cutter that is well 10 adapted for all the purposes heretofore designated, even though I have herein shown and described the invention as consisting of certain detail structural elements it is nevertheless to be understood that some changes 15 may be made therein without effecting the spirit and scope of the appended claim.

Having thus described the invention, what I claim is:—

In a cutting machine of the class described, a vertical standard, a pair of elongated hollow guide arms arranged horizontally in superposed relation on the standard, the bore of the upper guide arm being greater than the bore of the lower guide 25 arm, bearings arranged in the bores of the arms at the ends thereof, the bearings associated with the upper guide arm being

adapted for vertical slidable movement therein, a shaft extending longitudinally through each bore and journaled for rotation in the respective pairs of bearings, means for rotating the shaft simultaneously, a feed roller upon the outer end of the lower shaft, a cutter on the outer end of the upper shaft, resilient means cooperating with the 30 35 40 45 50 slidable bearings for normally urging the outer carrying shaft away from the feed roller carrying shaft, said resilient means including an elongated lever pivoted at its inner end within the bore of the upper arm below the shaft, the bearing in the upper arm adjacent the outer end thereof being formed with a slot in the lower portion thereof, the outer end of said lever being disposed in said slot and engaging said bearing, an expandible coil spring interposed between the intermediate portion of the lever and the lower portion of the upper guide arm, and manually operable means for moving the upper shaft downwardly toward the lower shaft whereby the space between the cutter and the feed roller may be adjusted.

In testimony whereof I affix my signature.

HARVEY PEPIN.
